UNITED STATES PATENT OFFICE.

HORACE W. LINDSEY, OF ATLANTA, GEORGIA.

EMERGENCY STRUCTURE FOR RAILWAY CARS.

1,417,185.

Specification of Letters Patent. Patented May 23, 1922.

Application filed November 19, 1919. Serial No. 339,096.

To all whom it may concern:

Be it known that I, HORACE W. LINDSEY, a citizen of the United States, residing at Atlanta, in the county of Fulton and State 5 of Georgia, have invented certain new and useful Improvements in Emergency Structures for Railway Cars, of which the following is a specification, reference being had therein to the accompanying drawing.

10 This invention relates to railway cars and, more especially, to mechanism carried thereby or associated therewith for controlling the brake-beam thereof in the event that it is abnormally displaced from position where- 15 by danger of accidents resulting from the dropping of the brake-beam upon the tracks is obviated or reduced to a minimum.

The primary object of the invention is to provide mechanism, of simple construction, 20 that is actuated by the abnormal movement of the brake-beam of a railway car, first to control the movement and position of the brake-beam and (if desired) to operate the associated air-brake system to bring the car 25 and, thus, the entire train, to a standstill.

A further object of the invention is to provide an auxiliary support for the brake-beam which is adapted to function for effectually controlling the movement and posi- 30 tion of the brake-beam in the event that the latter is actuated beyond prescribed limits of movement with consequent danger that it would then drop down upon the underlying tracks and derail the car or otherwise cause 35 serious damage thereto.

A still further object within the contemplation of the invention is to provide, in conjunction with the aforementioned auxiliary brake-beam support, means associated with 40 the air-brake system of the train whereby, after the brake-beam has reached a predetermined position during its abnormal movement away from normal, it will operate a valve in the system and thereby effect opera- 45 tion of the brakes to bring the train to a stop.

With these and other objects in view, the invention includes, broadly—in conjunction with the usual brake-beam of a railway car 50 and the supports or hangers whereby it is maintained in normal position and in operative relation to function for positioning the brakes in respect to the car wheels—an auxiliary support for the brake-beam adapted, 55 itself, to function in the event that the usual supports for the brake-beam becomes broken

or otherwise damaged; there being preferably associated with this support a connection with the air-brake system of the car whereby, if the auxiliary support is actuated 60 beyond a predetermined point, it will operate the air-brake system automatically.

The invention, more specifically defined, resides in a structure which includes one or more members connected to a stationary part 65 of the car and also to the brake-beam thereof, each of the members being of a construction and form to permit a certain amount of movement of the brake-beam in its normal operation of positioning the brakes in 70 respect to the wheels and operating to guide the brake-beam in its movement in the event that it becomes disengaged from its usual supporting instrumentalities and preventing it from dropping down upon the underlying 75 tracks or under the wheels of the car; and, in some instances, this structure is associated with operating mechanism connected to the air-brake system of the car whereby the system is actuated if the brake-beam moves 80 beyond a certain point but under the control of the member, so that, in addition to controlling the movement and the position of the brake-beam, the member then also functions as a component of the air-brake sys- 85 tem to operate it.

I am aware that it is not broadly new to associate with the brake-beam of a car means connected to the air-brake system thereof for operating the same in the event 90 that the brake-beam is abnormally displaced; but, so far as I am aware, it is new to associate with such a structure means for controlling the movement and position of the brake-beam in the event that it becomes 95 abnormally displaced so that, in addition to operating the air-brake system, it will be precluded from dropping onto the rails or passing under the wheels of the car, and this I claim to be of my invention.

In order that the invention may be more readily understood, I have disclosed two embodiments of the same in the accompanying drawings; but it will be apparent therefrom, as well as from the description which follows, that the invention is susceptible of a wide range of modification and variation without departing from the salient features or sacrificing any of the underlying principles of the invention; and in these drawings:

Fig. 1 is a view in top plan of a car truck with my invention embodied therein;

Fig. 2 is a view in vertical longitudinal section, on the line 2—2 Fig. 1;

Fig. 3 is a fragmentary view showing a brake-beam and my auxiliary beam-support 5 associated therewith;

Figs. 4, 5 and 6 are fragmentary views, mostly in elevation, and more or less diagrammatic, showing (in Fig. 4) the normal position of the parts; and (in Fig. 5) the 10 position of the parts when the brake-beam is elevated away from normal position; and (in Fig. 6) the position of the parts when the brake-beam has been displaced downwardly away from normal position, the 15 auxiliary hanger, in this figure, appearing in full lines in one of its abnormal positions and, in dotted lines, a different abnormal position of the hanger wherein it is locked or blocked against upward movement; 20 and

Fig. 7 is a fragmentary view, in perspective, of a brake-beam and my auxiliary support associated therewith; the latter being independent of the operative connection between the brake-beam and the valve-operating lever.

Referring to these drawings:

The reference-numeral 1 designates, generally, the truck of a railway-car of usual 30 construction, and which includes a truck-bolster 2, a truck frame 3, axles 4, wheels 5 thereon, and a brake-beam 6 extending transversely of the car but juxtaposed to the bolster, and which carries the usual brake-foot 7 35 on which is disposed a brake-shoe 8. The brake-beam is sustained in normal position by one or more links or hangers 9 connected to the truck-bolster and to the brake-beam, as shown, one adjacent each end thereof. The 40 particular form of these hangers for the brake-beam is, so far as my invention is concerned, immaterial; but I elect to utilize the usual types thereof which are found to be most efficient in modern practice.

45 Inasmuch as a sudden or emergency operation of the brakes might, and usually does, move the brake-beam to an abnormal extent, either the beam itself (at the point of its connection with said hangers) is, or the 50 hangers themselves are, broken; whereupon, as the brake-beam is then unsustained, it will either drop down upon the tracks, or pass under the wheels, or be thrown upwardly against parts of the truck so that, 55 eventually, it will drop down upon the tracks or pass under the wheels and effect a derailment of the car: This sort of accident is quite usual at the present day, and at least 75% of the derailment-accidents 60 on railway trains are due to the abnormal displacement of the brake-beam and its passing under the wheels with consequent derailment of the car. As already mentioned, 65 it has heretofore been proposed to connect the brake-beam with the air-brake system

of the car so that abnormal movement of the brake-beam will operate the system and bring the car to a stop; but, it frequently happens that, before the car can be brought to a standstill, the brake-beam will have 70 passed under the wheels and caused derailment. Hence, I propose to associate with the structure just mentioned means connected to or associated with the brake-beam to guide it in its abnormal movements and 75 effectually hold it against detachment from the car so that it will, then, be precluded from falling on the rails and effecting a derailment.

To this end, I provide what I shall herein 80 designate as an auxiliary support from the brake-beam; and this support comprises a member 10 which is permanently attached either to the truck-frame (as shown), to the truck-bolster, or to some other part of the 85 car. The particular manner of attaching this auxiliary support is immaterial, so long as its attachment is of such a character as to withstand strain upon the support in the event that the brake-beam is displaced from 90 normal position. I prefer to provide at least two of these members 10, each member being associated with one end of the brake-beam, as shown.

95 Each of these auxiliary members—which may also serve as a hanger—is formed as an irregularly-shaped link or element made preferably of round bar-iron or steel and provided with upper and lower eyes or lugs 11 and 12 for effecting an attachment of 100 the member to the truck-frame, as already mentioned.

105 Each of these members 10 comprises an elongated vertical section 13 formed by two parallel portions 14 and 14^a; two elbow-sections 15 and 15^a and an enlarged horizontal section 16. Between these several portions is an opening or space.

110 Loosely encircling the portion 15 is a link-element 17 adapted to slide upon this section and in the said opening or space; and, during an abnormal movement of the element, it may pass around the elbow-section 15^a and into the enlarged space or area 115 18 formed by the section 16, as will be presently explained.

120 Preferably and as shown, the brake-beam itself is jointed or otherwise secured, as at 19, to the link 17, the latter forming the active connection between the brake-beam 125 and the auxiliary support 10.

Rigidly or loosely connected to the link 17—as may be desired or as will best meet particular conditions—is an upstanding valve-operating element 20 provided with an elongated longitudinal slot 21. Operatively associated with the element 20 is a valve-opening lever 22, the latter carrying, at one end, a pin 23 adapted to move in the slot 21. The lever 22 is, preferably, pivoted to 130

and operates the valve 24, the latter (of usual construction) being disposed on a branch-pipe 25 extending from a main train-line or air-pipe 26 forming a part of the air system of the train. It is to be understood that there will preferably be as many of the branches 25 as there are wheels on the car; and that, likewise, there will be a brake-beam for each pair of wheels with a corresponding number of other parts and instrumentalities of the kind above described.

Operation: Assuming that the wheels of the car (as viewed in Fig. 5), are revolving in a clockwise direction, and that it becomes necessary for the engineer of the train to operate the brakes suddenly, and if, then, the engagement of the brakes with the wheels or some other action results in the breaking of the beam-hanger which connects the beam to the truck-bolster, with consequent abnormal displacement or dislocation of the beam; then, my improved beam-controlling structure—embracing the members 10 and the links 17—becomes active in order that the beam may not be carried (by reason of the engagement of the brakes with the wheels) into a position to cause an accident. To this end, the members 10 function to guide the links 17 in their upward movement (when carried in that direction by the beam) until the links reach the upper end of the section 13 of the member 10, at which point the brake-beam will thereby be held against further upward movement. Normally, the pin 23 will occupy a position at the lower end of the slot 21; and, when the link 17 is raised in the manner just explained, the valve-opening lever 22 will be lifted but without operating the valve 24.

If, however, the wheels of the car are rotating in a counter-clockwise direction, and if, then, the engagement of the brakes with the wheels results in the disconnection of the brake-beam from its hangers, my improved structure, as above described, will then function to control the downward movement of the brake-beam; and this is accomplished by the link 17 sliding downwardly, being guided in its movement by the vertical section 13 of the member 10. If such downward movement be such as to position the link 17 at the elbow-section 15 of the member 10, the latter will guide the brake-beam into its enlarged area 18 and there hold or lock it (as shown in Fig. 6) and prevent its further movement or dropping onto the underlying rails, the elbow portions 15 and 15^a contributing to this result. It is to be understood that the slot 21 in the valve-operating element 20 is of such length as to permit the element to have considerable downward movement or lost motion—as, for instance, down to a position adjacent the elbow-section 15—whereupon

the pin 23 will have moved to the top of the slot 21 and, then, the valve-opening lever 22 will be pulled downwardly and result in the opening of the valve 24 to release the air and, thus, operate the brakes 70 and stop the car, and the train, if there be several cars. The operation of the air system, by the opening of one or more of the valves 24, will, of course, occur generally when the brakes have not otherwise been 75 operated, as by the engineer of the train, inasmuch as the dislocation of the brake-beam 6 may also occur otherwise than during the operation of the brakes. In Figs. 4, 5, and 6, I have shown the relative positions 80 of the parts of my improved structure as just explained. In the operation of valve 24, link 17 has a movement vertically in a free path until stopped by the upper limit of slot 13; then downwardly until elbow 15^a 85 is reached, when this movement is translated angularly to the vertical into an approximately horizontal direction. It is found that this arrangement insures a gradual and not too sudden actuation of the valve. 90

Modifications: In Fig. 7, I have shown a somewhat modified form of construction; this involving the attachment of the valve-operating element 20 directly to the brake-beam 6 in lieu of attaching it to the link 17, as above-described: In this arrangement, the operation of the element 20 is effected, not directly by the link 17, but by the movement of the brake-beam itself. 95

It is to be understood that my invention 100 is applicable to any type of car in which a brake-beam is employed; and, also, that the auxiliary beam-hanger herein described may be used in conjunction with an air-brake system or not, as may be desired. 105

From the foregoing, it will be perceived that I have disclosed an effective structure, both for controlling the movement and position of the brake-beam and, also, for operating the air system of the car, in an emergency; that I have now described the principles of operation of the structure; and that I have made apparent its advantages and principal features. It is to be understood, however, that I do not limit myself 110 to the particular aggroupments of the parts, nor to the special manner of relating them one to the other, except in so far as the structure involves, as a primary instrumentality, 115 an auxiliary brake-beam support that functions only in the event of the abnormal dislocation of the brake-beam and which, when functioning, guides the brake-beam to a point where its abnormal movement can be effectually arrested and be there maintained 120 against danger of dropping upon the underlying tracks or passing under the wheels to cause derailment of the car. 125

What I claim is:

1. An emergency structure for railway- 130

cars including in combination a brake-beam, hangers therefor, a truck-bolster to which the hangers are connected, an auxiliary beam-support associated with said hangers and comprising an angular member, a connecting-element between the support and the beam and slidable on the support, first in a vertical direction and then in an approximately horizontal direction, the member being formed with an enlargement into which the element is disposed by the abnormal movement of the brake-beam, and an associated air-brake system operable by movement of the connecting-element.

15. 2. An emergency structure for railway-cars including in combination a brake-beam, hangers therefor, a truck-bolster to which the hangers are connected, an auxiliary beam-support associated with said hangers and comprising an angular member, a connecting-element between the support and the beam and slidable on the support, first in a vertical direction and then in an approximately horizontal direction, the member being formed with an enlargement into which the element is disposed by the abnormal movement of the brake-beam, and an associated air-brake system including a valve and a connection between the valve and the element whereby abnormal movement of the element will operate the valve.

3. An emergency structure for railway-cars including a truck, a truck-bolster carried thereby, a brake-beam juxtaposed to the bolster, a hanger for connecting the brake-beam to the bolster, an auxiliary beam-support adapted to function to sustain the brake-beam if it becomes dislocated and of angular form to provide a plurality of operating sections angulated to each other, a connecting-link attached to the brake-beam and having a sliding movement on the support, first in one direction and, then, in an angular direction, one section of the support being enlarged to receive and hold the connecting-element when the brake-beam is abnormally dislocated, and a valve-device operable by abnormal movement of said brake-beam.

4. An emergency structure for railway-cars including a truck, a truck-bolster carried thereby, a brake-beam juxtaposed to the bolster, a hanger for connecting the brake-beam to the bolster, an auxiliary beam-support adapted to function to sustain the brake-beam if it becomes dislocated and of angular form to provide a plurality of operating sections angulated to each other, a connecting-link attached to the brake-beam and having a sliding movement on the support, first in one direction and, then, in an angular direction, one section of the support being enlarged to receive and hold the connecting-element when the brake-beam is abnormally dislocated, an air-brake system carried by the car and including an emer-

gency-valve and a connection between the valve and the connecting-element whereby, by an abnormal movement of the element, the valve is operated to release air therefrom from the system.

5. An emergency structure for railway-cars including a truck, a bolster carried thereby, a brake-beam juxtaposed to the bolster, hangers connecting the beam to the bolster, an auxiliary-support for the beam adapted to function by dislocation of the beam from the hangers and comprising a plurality of members, each angular in form to present a plurality of sections angulated to each other, one section thereof being formed with enlargement, a connecting-element attached to the brake-beam and having movement in relation to the angular member, first in a substantially vertical direction and, then, in an approximately horizontal direction and into said enlargement whereby it is held against further abnormal movement, a valve-operating element associated with the brake-beam, a valve-opening lever connected to the valve-operating element, a valve controlled by the lever, and an air-brake system associated with the valve.

6. An emergency structure for railway-cars including a truck, a bolster carried thereby, a brake-beam juxtaposed to the bolster and movable in relation thereto, a valve-device operatively connected to said brake-beam, hangers associated with the bolster for normally sustaining the brake-beam, means associated with the brake-beam for controlling its movement and position in the event of its abnormal movement in relation to the bolster; said means comprising an auxiliary hanger associated with the bolster and inactive during the normal movement of the brake-beam but automatically rendered active by an abnormal movement of the brake-beam, said auxiliary hanger comprising an angular member having a plurality of operating sections angulated to each other, and a connection between the auxiliary hanger and the brake-beam whereby abnormal movement of the beam is guided by the auxiliary hanger, first in a substantially vertical direction and then in an approximately horizontal direction.

7. An emergency structure for railway-cars including a truck, a bolster carried thereby, a brake-beam juxtaposed to the bolster and movable in relation thereto, hangers associated with the bolster for normally sustaining the brake-beam, means associated with the brake-beam for controlling its movement and position in the event of its abnormal movement in relation to the bolster; said means comprising an auxiliary hanger associated with the bolster and inactive during the normal movement of the brake-beam but automatically rendered active by an abnormal movement of the brake-

beam, said auxiliary hanger comprising an angular member having a plurality of operating sections angulated to each other, a connection between the auxiliary hanger and the brake-beam whereby abnormal movement of the beam is guided by the auxiliary hanger, first in a substantially vertical direction and then in an approximately horizontal direction; in combination with an auxiliary air-valve operatively associated

with the auxiliary hanger and rendered operative by the abnormal movement of the same.

In testimony whereof I affix my signature in presence of two witnesses.
